US00D960581S

(12) **United States Design Patent** (10) **Patent No.:** **US D960,581 S**
(45) **Date of Patent:** **** Aug. 16, 2022**

(54) **TOOTHBRUSH HEAD**

(71) Applicant: **The Gillette Company LLC**, Boston, MA (US)

(72) Inventors: **Christine Hallein**, Frankfurt (DE); **Uwe Jungnickel**, Koenigstein (DE); **Dominik Langhammer**, Frankfurt (DE)

(73) Assignee: **The Gillette Company LLC**, Boston, MA (US)

(**) Term: **15 Years**

(21) Appl. No.: **29/659,068**

(22) Filed: **Aug. 6, 2018**

(30) **Foreign Application Priority Data**

Feb. 9, 2018 (WO) 6333101

(51) **LOC (13) Cl.** **28-03**

(52) **U.S. Cl.**

USPC **D4/101**

(58) **Field of Classification Search**
